CLAIM

The ornamental design for a display screen or portion thereof with graphical user interface, as shown and described.

DESCRIPTION

The patent file contains at least one drawing executed in color. Copies of this patent with color drawings will be provided by the Office upon request and payment of the necessary fee.

FIG. 1 is a front view of a display screen or portion thereof with graphical user interface showing our new design according to a first embodiment; and,

FIG. 2 is a front view of a display screen or portion thereof with graphical user interface showing our new design according to a second embodiment.

The outermost rectangle in each figure illustrates a display screen or portion thereof. The portion of the outermost rectangle in each figure illustrated with dashed broken lines forms no part of the claimed design. The remaining broken lines in each figures illustrate portions of the graphical user interface that form no part of the claimed design.

The gray shading in FIG. 2 illustrates a contrast of appearance.
